(57) **CLAIM**

The ornamental design for a dongle for receiving digital TV broadcasting, as shown and described.

DESCRIPTION

FIG. 1. is a front elevational view of a dongle for receiving digital TV broadcasting showing my design;

FIG. 2. is a rear elevational view thereof;

FIG. 3. is a left elevational view thereof;

FIG. 4. is a right elevational view thereof;

FIG. 5. is a top plan view thereof;

FIG. 6. is a bottom plan view thereof;

FIG. 7. is a perspective view thereof;

FIG. 8. is a perspective view thereof when its cover for a USB plug is opened;

FIG. 9. is a perspective view thereof, with the cover shown removed for ease of illustration; and,

FIG. 10 is a perspective view thereof, with the cover shown removed for ease of illustration, and its RF antenna is extended.
